UNITED STATES PATENT OFFICE.

CLARENCE F. AMES, OF AKRON, OHIO.

CORE.

1,279,214.

Specification of Letters Patent. Patented Sept. 17, 1918.

Application filed March 11, 1918. Serial No. 221,728.

To all whom it may concern:

Be it known that I, CLARENCE F. AMES, a citizen of the United States, residing at Akron, in the county of Summit and State 5 of Ohio, have invented new and useful Improvements in Cores, of which the following is a specification.

This invention relates to improvements in cores for the manufacture of the outer shoes 10 of double tube pneumatic tires. The object of the invention is to provide a core comprising a plurality of separable segment-shaped members which when united form an annulus and which are capable of being 15 collapsed and also longitudinally extended during the vulcanizing operation for the purpose of stretching the fabric of the tire shoe during vulcanization.

The invention further contemplates the 20 provision of means for longitudinally extending or expanding the core when desired and also means for holding the various segment-shaped sections together.

With the foregoing and other objects in 25 view, the invention consists in the novel construction, combination and arrangement of parts constituting the invention to be hereinafter specifically described and illustrated in the accompanying drawings which 30 form a part hereof wherein is shown the preferred embodiment of the invention, but it is to be understood that changes, variations and modifications can be resorted to which come within the scope of the matter 35 hereinafter claimed.

In the drawings in which similar reference numerals indicate like parts in the different figures,

Figure 1 is a plan view of a portion of a 40 core embodying the present invention with a portion broken away.

Fig. 2 is a sectional view of the end of one of the sections.

Fig. 3 is a similar view of the complementary end of the adjacent section.

Fig. 4 is a fragmentary view of the side of a core illustrating one of the joints between sections.

Fig. 5 is a view partly in section and 50 partly in side elevation of another form of joint employed in the core.

Fig. 6 is a transverse sectional view of a 55 mold with a core positioned therein with the members of the mold separated and in the position which they assume previous to the application of pressure to the mold.

Fig. 7 is a view similar to Fig. 6 with the mold completely closed.

Fig. 8 is a fragmentary transverse sectional view of a portion of the core.

Fig. 9 is a view similar to Fig. 6 showing different means for circumferentially expanding or extending the core, and

Fig. 10 is a ring employed in connection with the mold shown in Fig. 9.

The core which forms the subject matter of the present invention comprises a plurality of separate segment-shaped sections adapted when united to form an annulus and with means for detachably connecting the 70 various segment-shaped sections together. The core comprises a plurality of sections 1, 2, 3, 4, 5 and 6 the outer portions of all of which are fashioned to impart the desired configuration to the interior of the tire 75 shoe which is to be manufactured thereon and all the sections are provided with inwardly-extending flanges 7 which are provided on one side with facial recesses which in the assembled condition of the core provide a continuous circumferential channel 80. The inner faces of the flanges are beveled or inclined for a purpose to be later described. Adapted to be seated in this channel is a locking ring 8 provided at one 85 or more places with threaded openings in which are mounted elevating screws 9. The section 1 constitutes the key section and is made wedge-shaped so that it may be easily withdrawn inwardly from the finished tire 90 shoe. The joints between the key section 1 and the two coadjacent sections 2 and 6 are temporarily covered by thin strips of metal 10 which are held in place by the material of the tire shoe during the building thereof. 95

The joints between the remaining sections are all similar and are best illustrated in Figs. 2 and 3 and for the purposes of illustration the sections 2 and 3 will be used.

The end of the section 2 used for illustration is provided with a projecting portion 11 and the outside portion of this projection 11 is chamfered at 12 so that the walls thereof are approximately conically fashioned or inclined and the end of the section 100

is closed by a plate 13 in the usual manner. The complementary end of the section 3 is provided with a recess 14 the edges of which are inclined at an angle approximating the 105 chamfered wall of the projection 11. The recess 14 constitutes a socket the inner or

bottom end of which is closed by a plate 15.

The projecting end 11 of the section 2 is adapted to seat in the recess 14 and the side walls of the recess 14 to overlap the chamfered parts of the projection 11 so that when the segments are united the exterior of the core will present a smooth and even surface on which the tire is built. The core is assembled by uniting the various sections 2, 3, 4, 5 and 6 by inserting the projecting ends 10 11 of the sections in the various sockets 14 after which the key section 1 is positioned. The strips 10 of thin sheet metal are then laid in place over the joints between the section 1 and the sections 2 and 6. The locking ring 8 is then positioned in the channel in the flanges 7 and driven to place, the channel preferably being somewhat wedge-shaped or having at least one inclined edge the ring being similarly provided. The core 15 is then ready for use in building the tire shoe. After the building up of a tire shoe on the core the core is laid in the lower half 16 of the mold and the locking ring 8 removed. The removal of the locking ring is 20 easily accomplished by rotating the screws 9 which engaging the flanges 7 lift the ring from its seat. The upper half 17 of the mold is then positioned. This section of the mold is provided with an inwardly-extending flange 18 having the inclined face 19 which engages the inner inclined faces of the flanges 7 as the mold members are clamped to place by means of the ordinary hydraulic press. The various members of 25 the core are forced outwardly or longitudinally extended or expanded to force the tire shoe 20 into engagement with the walls of the mold thereby stretching the fabric and removing wrinkles and other irregularities 30 in the construction of the same.

In order to utilize molds already in existence which are not equipped with a flange 18 and are of the construction shown in Fig. 9 and in which the upper mold is denominated by the reference numeral 21 and the lower member by the numeral 22 I employ 35 the spreading ring shown in Fig. 10 comprising a flange 23 which is adapted to seat on the upper face of the upper mold 21 and

with a downwardly-extending annular flange 24 having a conically-formed lower end 25 which is adapted to engage the inner inclined faces of the various flanges of the core sections and when forced downwardly by the pressure exerted by the press in which the molds are placed accomplish the same function as is accomplished where the upper mold sections is provided with the inwardly-extending flange 18 thereby enabling old molds to be used with this core and also permitting the circumferential expansion or extension of the core therein during the closing of the mold. It will be obvious that the core may be circumferentially-extended due to the telescopic joints between the various sections and at the same time present a smooth and even surface to the inner face of the shoe. The joints between the key section 1 and the two adjacent sections 2 and 6 and also joints in case of a separation 70 due to the extension of the core in the mold are covered by the thin strips of metal 10 so that a smooth and even surface is imparted to the interior of the finished tire shoe. 75

I claim,

A core of the character described comprising a plurality of separable segment-shaped sections having inwardly-extending flanges the inner faces of which are inclined and the lateral faces provided with grooves, which, in the assembled condition of the sections provide an annular channel, an annular ring insertible in said channel and adapted to hold said sections together during the building up of a tire shoe on said core, wedging means for moving said sections radially outwardly to circumferentially expand said core and covering means applied over the joints between the contiguous sections to cover the openings between contiguous sections caused by the movement thereof during the expansion of the core. 80 85

In testimony whereof I have hereunto set my hand in presence of two subscribing witnesses. 90 95

CLARENCE F. AMES.
